PAUL YUNGLING, OF LOS ANGELES, CALIFORNIA

COLLAR SPLITTER

Application filed May 29, 1929. Serial No. 366,907.

This invention relates to a device in the nature of an overshot which may be operated, by an upward pull to engage a cylindrical string such as a tubing string. A more specific form of the invention appertains to a device as above described which may be operated to split collars which serve as couplings between adjoining sections of a tubular string, such as well casing, drill pipe and the like. Hereinafter, the term "tubing" is used in the broad sense to include well casing, drill pipes and any equivalent cylindrical string. It is desirable in oil well work to cut off sections of a tubular string when the latter is in the well hole, especially when the string is stuck or "frozen" in the hole. By parting the string at a collar, the upper section may be removed. It is therefore advantageous to provide a tool which may be positioned at a selected collar and is operable to split the latter so as to release the joints of tubing coupled thereby.

The objects of this invention are: first, to provide a device which may be slipped over a string of tubing and lowered to a selected position and then upon elevation will contact with the tubing; second, to provide a device which may be slipped over a string of tubing and lowered to a selected position and then upon elevation will contact with the tubing; second, to provide a device which may be slipped over the string of tubing and lowered to a selected collar, then by an upward pull split the collar; third, to provide a tool which will first cut the collar and thereupon open the cut so made; fourth, to provide a tool which will obtain a hold upon the parted tubing so as to strip the collar from the lower joint of tubing; and fifth, to provide a splitter which is durable, simple, strong and is operable with a minimum of applied force.

These objects together with other objects and corresponding accomplishments are obtained by means of the embodiments of my invention illustrated in the accompanying drawings, in which:—

Fig. 1 is an axial section through a collar splitter showing a tubing string in elevation, the operating parts being shown in their

initial position splitting a collar; Fig. 2 is a section as seen on the line 2—2 of Fig. 1; Fig. 3 is a view similar to Fig. 1 showing a fragment of the tool as seen on the line 3—3 of Fig. 1; Fig. 4 is a view similar to Fig. 3 showing the gash or cut opened by the piercing dogs, the tool having been advanced to its final position before stripping occurs; Fig. 5 shows side and front elevations of a piercing dog; Fig. 6 is a vertical section showing details of the mounting of a piercing dog; Fig. 7 shows a side and front elevation of a stripping dog; Fig. 8 is a perspective view of a wedge block for supporting the gashing cutters.

Referring more particularly to Figs. 1 to 8 inclusive, of the drawings, A indicates a string of drill pipe having a coupling collar a. Disposed over the drill pipe string is a tubular operating string B hereafter referred to as the tool or fishing string. Attached to the tool string is a body C carrying a gashing means indicated generally by D. Piercing mechanism is indicated generally by E and stripping means by F.

The body comprises an adapter collar 15 having a seat 16 for a spring. Attached to the collar 15 is a cylindrical shell 17 having a tapered intermediate portion 18 provided with a seating shoulder 19. Below the tapered portion the bore of the shell is of increased diameter and attached to the bottom is an adapter collar 20 providing a shoulder 21. The collars 15 and 20 are internally threaded to adapt them to receive tubing, the tool string B being connected to the collar 15.

Mounted within the body at the tapered surface 18 are ring segments 22a and 22b, their adjacent ends being spaced to define slide ways for wedge blocks. The rings are shown secured to the shell by means of machine screws 23. Slidably mounted in the ways are wedge blocks 24a and 24b. The wedge blocks have inclined faces corresponding to the tapered surface 18 so as to ride thereon. The inner faces of the wedge blocks are recessed and journalled therein are gashing roller cutters 25a and 25b. Retaining blocks 26a and 26b form part of the wedge

blocks and are for the purpose of convenience of assembly, permitting removal and replacement of the cutters. Seated on the wedge blocks and resting against the spring seat 16 is a compression spring 27 tending to move the wedge blocks to their lower positions resting upon seat 18 with the cutters disposed in their innermost position.

Mounted upon the shoulder 21 is a ring 28 secured thereto by screws 29. At points 90° apart on the ring 28 are pairs of ears 30, two diametrically opposite pairs being in registration with the gashing rollers. A bearing member 31 is secured in position between each pair of the ears by a dowel pin to define a rounded bearing surface for piercing dogs 32 to thrust against. The dogs are pivotally retained on the ears by means of screws 33. Each piercing dog has a point 34 and an outer cutting edge 35. The points of the piercing dogs are disposed below the gashing rollers a distance equal to about one half the length of a collar *a*. A stop shoulder 36 is provided on each dog to limit its inward swinging movement. Leaf springs 37 secured to the dogs engage the shell and tend to maintain the piercing dogs in their innermost position.

Between each pair of ears 30, at 90° to the gashing rollers, are stripper dogs 39, supported on bearing blocks and retained by screws in the same manner as piercing dogs 32. Dogs 39 have lifting shoulders 40 for engaging the under edge of a collar, the shoulders being disposed below the points of the piercing dogs. The stripper dogs are urged to swing inwardly by leaf springs 41, a stop shoulder 40' being provided on each dog to limit its inward swinging movement.

With the parts assembled as shown in Fig. 1, the splitter is placed over the drill pipe to be parted and lowered to the collar to be split. Lowering is effected by means of the tool string B. As the splitter passes downwardly, the dogs ride over the collars but are maintained in contact with the drill pipe string. The gashing rollers are maintained in contact with the drill pipe string and will ride freely over the collars, as the wedge blocks may be moved upwardly against the action of compression spring 27 and thereby outwardly for the rollers to clear the collars. When the tool has been positioned with the gashing cutters below the collar to be split, the splitter is pulled upwardly, the wedge blocks being forced into their lower positions by the upward drag and the cutters into the collars causing them to gash the collar as indicated by 42 in Fig. 3. After about one half of the collar has been gashed or cut, the piercing dogs 32 enter between the bottom of the cut and the pipe. A further pull causes the stripper dogs to engage the lower edge of the collar and the piercing dogs to split it. Further pulling spreads the collar,

as indicated at 42a (Fig. 4), and strips it from the lower joint of pipe. The stripper dogs serve then for lifting the upper parted section of the drill pipe.

What I claim is:—

1. A collar splitter for tubular strings comprising a hollow body adapted to be slipped over a tubing string, gashing members having cutters movably mounted in said body, means to cause said cutters to be projected inwardly against the string upon upward movement of the body in relation to the string, and piercing dogs pivotally mounted on said body below said cutters and in alignment therewith, said dogs being urged inwardly toward the string.

2. A collar splitter for tubular strings comprising a hollow body adapted to be slipped over a tubing string, wedge members movably mounted on said body so as to be caused to be moved inwardly toward the string to be cut upon upward movement of said body in relation to said wedge members, gashing cutters mounted on said wedge members, and piercing dogs pivotally mounted on said body below said cutters and in alignment therewith, said dogs being urged inwardly toward the string.

3. A collar splitter for tubular strings comprising a hollow body adapted to be slipped over a tubing string, wedge members movably mounted on said body so as to be caused to be moved inwardly toward the string to be cut upon upward movement of said body in relation to said wedge members, gashing cutters mounted on said wedge members, resilient means tending to move said wedge members downwardly in said body, and piercing dogs pivotally mounted on said body below said cutters and in alignment therewith, said dogs being urged inwardly toward the string.

4. A collar splitter for tubular strings comprising a hollow body adapted to be slipped over a tubing string, said body having an inclined surface converging downwardly and inwardly, wedge blocks slideable on said surface, gashing cutters on said wedge blocks, and piercing dogs pivotally mounted on said body below said cutters and in alignment therewith, said dogs being urged inwardly toward the string.

5. A collar splitter for tubular strings comprising a hollow body adapted to be slipped over a tubing string, said body having an inclined surface converging downwardly and inwardly, wedge blocks slideable on said surface, gashing cutters on said wedge blocks, resilient means tending to move said blocks downwardly with relation to said body, and piercing dogs pivotally mounted on said body below said cutters and in alignment therewith, said dogs being urged inwardly toward the string.

6. A collar splitter for tubular strings com-

- prising a hollow body adapted to be slipped over a tubing string, said body having an inwardly extending spring seat at the upper end of its bore, inwardly extending blocks 5 seats spaced below said spring seats, an inclined surface intermediate said seats converging downwardly and inwardly, wedge block members mounted on said surfaces, cutters on said wedge blocks, a compression 10 spring disposed between said wedge blocks and said spring seat, and piercing dogs pivotally mounted on said body below said cutters and in alignment therewith, said dogs being urged inwardly toward the string.
- 15 7. A collar splitter for tubular strings comprising a hollow body adapted to be slipped over a tubing string, gashing members having cutters movably mounted in said body, means to cause said cutters to be projected 20 inwardly against the string upon upward movement of the body in relation to the string, piercing dogs pivotally mounted on said body, and stripper dogs having lifting shoulders mounted on said body and laterally 25 movable inwardly toward said string, said shoulders being disposed below the active ends of said piercing dogs.
- 30 8. A collar splitter for tubular strings comprising a hollow body adapted to be slipped over a tubing string, gashing members having cutters movably mounted in said body, means to cause said cutters to be projected 35 inwardly against the string upon upward movement of the body in relation to the string, piercing dogs pivotally mounted on said body below said cutters and in alignment therewith, said dogs being urged inwardly toward the string, and stripper dogs having lifting shoulders mounted on said 40 body and laterally movable inwardly toward said string, said shoulders being disposed below the active ends of said piercing dogs.
- 45 9. A collar splitter for tubular strings comprising a hollow body adapted to be slipped over a tubing string, gashing members having cutters movably mounted in said body, means to cause said cutters to be projected 50 inwardly against the string upon upward movement of the body in relation to the string, piercing members mounted on said body below said gashing members in alignment with said cutters to engage and open the cuts made by said cutters, and stripper dogs having lifting shoulders mounted on said 55 body and laterally movable inwardly toward said string, said shoulders being disposed below the active ends of said piercing dogs.
- 60 10. A collar splitter for tubular strings comprising a hollow body adapted to be slipped over a tubing string, gashing members having cutters movably mounted in said body, means to cause said cutters to be projected 65 inwardly against the string upon upward movement of the body in relation to the string, piercing dogs pivotally mounted on
- said body at their lower ends below said cutters and in alignment therewith, springs urging said dogs inwardly toward the tubular string, and stripper dogs pivotally mounted on said body and having lifting shoulders disposed below the active ends of said piercing dogs, said stripper dogs being urged toward said string. 70
- In witness that I claim the foregoing I have hereunto subscribed my name this 10th day 75 of May, 1929.
